UNITED STATES PATENT OFFICE.

WILLIAM C. TREGONING, OF CLEVELAND, OHIO, ASSIGNOR, BY MESNE ASSIGNMENTS,
TO BENJAMIN ELECTRIC MANUFACTURING COMPANY, OF CHICAGO, ILLINOIS, A
CORPORATION OF ILLINOIS.

ELECTRICAL ATTACHMENT-PLUG.

1,328,774.

Specification of Letters Patent. Patented Jan. 20, 1920.

Application filed February 6, 1913, Serial No. 746,481. Renewed February 10, 1919. Serial No. 276,244.

To all whom it may concern:

Be it known that I, WILLIAM C. TREGONING, citizen of the United States, residing at Cleveland, in the county of Cuyahoga and 5 State of Ohio, have invented certain new and useful Improvements in Electrical Attachment-Plugs, of which the following is a specification.

My invention comprises an electrical attachment plug constructed substantially as 10 herein shown and described and more particularly pointed out in the claims.

One of the objects of the invention is to 15 provide a simple and practical screw plug wherein a relatively small number of parts are particularly related to permit the screw member thereof to be rotated without twisting the electrical cable connection. A further object of the invention is to provide a 20 plug of this character wherein the terminal supporting member and the said screw member are separably united by a split ring providing a rotatable bearing between the parts. Another object of the invention is to 25 provide a device of this character wherein the cable connecting member is particularly constructed to relieve the wire terminal connection of all strains. Further objects and advantages of the invention will be obvious 30 from the detailed description given below, in connection with the accompanying drawings illustrating various modifications of the invention.

In the accompanying drawings, Figure 1 35 is a side view of my improved attachment plug shown full size and as assembled for use. Fig. 2 is a perspective view of the two main plug parts in such separable relations as occur in making terminal connections, 40 and Fig. 3 is a perspective view of the split locking ring. Fig. 4 is a sectional view centrally of a complete plug considerably enlarged. Figs. 5 and 6 are perspective and 45 sectional views respectively of two modified forms of the inner terminal-support and cable-connecting member of my invention.

Detailing my invention, the same comprises a hand-hold member 2 made of insulating material, such as a rubber composition or porcelain, and this member is of cylindrical form and has a roughened and milled outer surface to provide a good finger grip to rotate the same. Member 2 is also provided with a reduced extremity 3 upon 55 which a screw-shell 4 is securely fastened to

permit screw-attachment with electric lamp sockets in general use, and is also constructed with a differential bore 5 and a rounded seat or channel 6 in its upper end surrounding said bore wherein a split ring 60 7 of spring metal may be removably confined and have a rotatable bearing, especially when said ring is engaged in locked relation with the butt basic portion of the plug, such butt basic portion consisting of a 65 tubular member or thimble 8 forming a rigid part of the inner plug member which guides and supports the wire-connecting terminals. Thus, thimble 8 is a cylindrical piece made of insulating material, either 70 rubber, composition or porcelain, and having an annular groove 9 to hold the bearing and locking ring 7. In Figs. 1 to 3 this piece 8 is shown as reduced in diameter at its lower or inner end to permit a sleeved and 75 shouldered connection to be made with the band part 10 of the two-legged yoke 12 which also comprises a larger bottom rim 14 of circular form and of a diameter to bear constantly against the inturned end 15 of 80 the screw-shell 4 when the plug parts are completely assembled and therethrough provide a path for the electric current from the screw-shell to the spreading legs of the yoke forming an integral or fixed part of the rim. 85 An ear 16 on one of the legs of the yoke carries a terminal screw 17 wherewith connection may be made with one wire 18 of the electrical cable or cord 20 when entered and extended through thimble 8. Said cable is 90 not only guided by the thimble, but is also preferably secured within the thimble to relieve and prevent end pull or strain upon the terminal connections and for this purpose I provide said thimble with internal threads 95 21 which start at the bottom of the smooth bore 22 in the top of said thimble and whereby the said thimble may be first sleeved and then screw-threaded upon the end of said cable,—the insulating body and the woven 100 covering of the cable being of a yielding character to permit such screw-threading operations without forming a screw-thread as a preliminary step in the cable itself.

To complete the electrical connection, it 105 is of course necessary to provide means to connect the other wire 19 of the cable with another contacting terminal for the plug and which, in the present instance, comprises the central metal cap 23 forming a 110

center contact secured to the outer end of the tip basic portion or insulating head 24 by a screw 25 which passes centrally through said head and screw-engages the angular metal bracket 26 having the terminal screw 27 for wire 19. The reduced extremity 3 of the hand-hold member 2 forms an insulating shield or sleeve which prevents short-circuiting between the screw-shell 4 and the terminal-screw 27 or wire 19. Head 24 is slightly recessed to seat the base of bracket 26 and is made of suitable insulating material to electrically insulate the bracket 26 from the rim 14 of the metal yoke which is shown as having its edge spun over the edge of the head. The bracket 26 is also preferably disposed with its upstanding portion at a point centrally between the two legs of the yoke so that ample room is given to connect and disconnect the wires at the binding screws and of course also to prevent short-circuiting between the parts. When all the parts are assembled, the spring ring 7 locks them together with a slight friction between the screw-shell and the yoke rim 14, thus giving a good electrical contact. However, the parts have perfect freedom of rotation so that hand-hold member 2 and the screw-shell may be jointly rotated without twisting the cable 20 when a socket attachment is made. In separating the hand-hole member from the terminal supporting body, one end of the split ring is lifted or sprung outward and the ring expanded and removed, which unlocks the parts, so that they may be taken apart as in Fig. 2 to permit of the attachment of the conducting wires to the binding-posts for the purpose of wiring the plug or to permit of the re-attachment of either one or both of such connecting wires in the event they become detached from the binding-posts. The device is readily assembled by slipping the threaded shell back into position and replacing the locking spring.

In Fig. 5 a single uniting leg 28 is shown which in a sense is the equivalent of the bracket 26, in that it becomes the terminal member for the wire that places the cap 23 and the fastening screw 25 in the electric circuit. As modified, the bracket is extended to unite with the thimble 8', a practical union being effected by molding said bracket within the thimble in the making thereof. Then in lieu of a contact rim 14 with legs I use a metal contact rim or band 14' with a short leg or ear 16' bent upwardly therefrom to hold a terminal binding screw for attaching the other wire that places the screw-shell in the electric circuit.

In Fig. 6 the device is modified to permit the terminal connections 29 and 30 to be molded within or upon the insulating thimble 8' and head 24', thereby uniting all said parts together. The part 29 extends

through the head 24' and is bent over at its outer end to provide a central contact for the plug in lieu of the separate cap 23 shown in the other figures.

While I have described the embodiments 70 of the invention illustrated in the drawings in considerable detail, it is to be understood that I do not desire to be limited thereto except as specified in the appended claims, since many changes and modifications may 75 be made without departing from the spirit and scope of the invention.

What I claim is:

1. In an electrical attachment plug, a hand-hold member having a screw-shell contact, an insulating thimble, and a head having a metal connecting member, a center contact, and a terminal binding screw for said contact rotatably mounted within said hand-hold member, and a spring ring to 80 secure said parts in fixed rotatable relation.

2. In an electrical attachment plug, two independently-rotatable elements, carrying separate electrical contacts, one of said elements comprising an insulating thimble 90 having a central bore with a smooth surface at its end, and a screw-thread intermediate its ends, a detachable terminal connection mounted on said thimble, and a movable bearing and locking ring rotatably and 95 detachably uniting the said elements.

3. In an electrical attachment plug, a separate thimble and head having an intermediate uniting metal part therefor, and one of said parts having an electric-current contact piece mounted thereon, in combination with a hand-hold member having a screw-shell engaged with said contact piece, and a split ring to rotatably and detachably unite said thimble and hand-hold member 100 together.

4. In an electrical attachment plug, a screw-shell and rotatable support therefor, contact terminals and an insulating support therefor comprising a separate head and 110 thimble, means to rotatably unite said shell support and said terminal supports, said thimble having a bore with internal screw-threads adapted to screw-engage with a cable connection when inserted therein to make 115 wire connections with said terminals.

5. An attachment plug comprising an insulating member, a center contact supported thereon, cord gripping means, a metallic member connecting said insulating member 120 and cord gripping means, and a binding screw threaded into said metallic member.

6. An attachment plug comprising an insulating member, a center contact supported thereon, cord gripping means, a metallic member connecting said insulating member and cord gripping means, and a binding screw threaded into said metallic member, said metallic member being electrically connected to said center contact.

7. An attachment plug comprising an insulating member having a substantially cylindrical opening therein, a substantially cylindrical cord gripping member rotatably mounted in said opening, and a shell contact supported by said insulating member. 5
8. An attachment plug comprising an insulating butt basic portion, an insulating tip basic portion, a conducting member connecting the butt basic portion and the tip basic portions and preventing movement of either portion with respect to the other when the parts are assembled, a center contact for the tip basic portion electrically connected to the conducting member, a screw shell rotatable with respect to the basic portions, a second conducting member attached to one of the basic portions and electrically connected to the screw shell, and a binding-post carried by each conducting member. 10
9. An attachment plug comprising an insulating butt basic member, an insulating tip basic member, a center contact supported by said tip basic member, a metallic member mechanically connecting said basic members and electrically connected with said center contact, a binding screw threaded into said metallic member, and a screw shell contact swivelly mounted with respect to said tubular member and base. 15
10. An attachment plug comprising a butt basic portion, a tip basic portion having a center contact, a conducting member secured to the tip basic portion and permanently fixed to the butt basic portion, a second conducting member mounted on one of the basic portions, a screw shell freely rotatable with respect to the basic portions and having a handhold, a binding-post carried by each conducting member, one of the conducting members being electrically connected to the screw shell while the other is electrically connected to the center contact, and supporting means for maintaining the screw shell in assembled relation to the basic portions without interfering with its rotation. 20
11. An attachment plug comprising an insulating tubular cord guiding member, an insulating head, a center contact supported by said head, a metallic member secured to said tubular member, and a screw extending through said head and threaded into said metallic member and electrically connected to said center contact, said metallic member having a screw threaded opening to receive a binding screw, and a screw shell contact swivelly mounted with respect to said tubular member and head. 25
12. An attachment plug comprising a butt basic portion, a tip basic portion, a conducting member having one end permanently secured to the butt basic portion and the other connected to the tip basic portion, a center contact for the tip basic portion electrically connected to the butt basic portion, a second conducting member attached to one of the basic portions and electrically connected to the screw shell, a binding-post threaded into each conducting member, and supporting means for maintaining the screw shell in assembled relation to the basic portions without interfering with its rotation. 30
13. An attachment plug comprising an insulating butt basic portion, an insulating tip basic portion, a conducting member having one end rigidly attached to the butt basic portion and its other end secured to the tip basic portion and securing the said portions from movement independently of each other when the parts are assembled, a second conducting member on one of the basic portions, a center contact for the tip basic portion, a screw rod passing through the tip basic portion and engaging one of the conducting members to electrically connect said center contact with said conducting member, and a screw shell electrically connected with the other conducting member and rotatable with respect to the basic portions. 35
14. An attachment plug comprising an insulating butt basic portion and a tip basic portion, the latter having a center contact, a conducting member attached at one end to the butt basic portion and at the other end to the tip basic portion, a second conducting member carried by one of the basic portions, a threaded shell rotatable with respect to the basic portions and having a handhold, one of said conducting members being electrically connected to the center contact and the other electrically connected to the threaded shell, and a binding-post directly carried by each conducting member, both said binding-posts being located within the threaded portion of the screw shell. 40
15. An attachment plug comprising an insulating butt basic portion, an insulating tip basic portion, a conducting member connecting the two basic portions to secure the same against movement independently of each other when the parts are in assembled relation, a second conducting member associated with one of the basic portions, a screw shell contact rotatable with respect to the basic portions, a center contact for the tip basic portion electrically connected with one of the conducting members, a lip on the other conducting member for electrical engagement with the threaded shell, and a binding-post on each conducting member. 45
16. An attachment plug comprising insulating butt basic and tip basic portions, a screw shell contact rotatable with respect to the basic portions and a center contact for the tip basic portion, a conducting member rigidly connecting the basic portions 50

when the basic portions are in assembled relation, a second conducting member mounted on one of the basic portions, one of the conducting members being electrically connected to the center contact and the other having a lip which is in electrical engagement with the screw shell, and binding-posts on the conducting members.

17. An attachment plug comprising a butt basic portion, a tip basic portion, a conducting member having one end secured to the butt basic portion and the other end connected to the tip basic portion, a center contact for the tip basic portion electrically connected to the conducting member, a screw shell contact rotatable with respect to the basic portions, a second conducting member affixed to one of the basic portions and electrically connected to the screw shell, a binding-post threaded into each conducting member, an insulating shield between the binding-posts for the center contact and the screw shell contact, and provision for maintaining the screw shell in assembled relation to the basic portions without interfering with the rotation.

18. An attachment plug comprising a butt basic portion, a tip basic portion, a conducting member having one end secured to the butt basic portion and the other end connected to the tip basic portion, a second conducting member carried by one of the basic portions, a center contact for said tip basic portion, a screw shell contact rotatable with respect to the basic portions, said contacts being electrically connected respectively with the conducting members, a binding-

screw threaded into each of said conducting members, an insulating shield between the binding-screw for the center contact conducting member and the screw shell contact, and means for maintaining the screw shell in assembled relation with respect to the basic portions without interference with its rotation.

19. An attachment plug comprising a butt basic portion, a tip basic portion, a conducting member having one end secured to the butt basic portion and the other end connected to the tip basic portion, a center contact for the tip basic portion, a screw shell contact rotatable with respect to the basic portions and having a hand-hold, two binding-screws located between said basic portions, one of said binding-screws being threaded into said conducting member, one of said binding-screws being electrically connected to the center contact and the other to the screw shell contact, an insulating lining for the screw shell integral with the hand-hold on the threaded shell and constituting a shield between the binding-screw for the center contact and the screw shell contact, and means for maintaining the screw shell in assembled relation with respect to the basic portions without interfering with its rotation.

In testimony whereof I affix my signature in presence of two witnesses.

WILLIAM C. TREGONING.
